(57) **CLAIM**

The ornamental design for a control unit for a climate control system, as shown and described.

DESCRIPTION

FIG. 1 is a perspective view of my new control unit for a climate control system;

FIG. 2 is a front view thereof;

FIG. 3 is a top view thereof;

FIG. 4 is a right side view thereof;

FIG. 5 is a rear view thereof;

FIG. 6 is a left side view thereof; and,

FIG. 7 is a bottom view thereof.

The surface markings illustrated in broken lines in FIGS. 1, 2, 4 and 6 and the surfaces and/or portions of surfaces bounded by broken lines in FIGS. 3 to 7 are provided for illustrative purposes only and form no part of the claimed design.
